L. DE FOREST.
APPARATUS FOR AMPLIFYING PULSATING ELECTRIC CURRENTS.
APPLICATION FILED JULY 22, 1915.

1,348,157.

Patented Aug. 3, 1920.

Lee de Forest Inventor
By his Attorney Samuel F. Darby

UNITED STATES PATENT OFFICE.

LEE DE FOREST, OF NEW YORK, N. Y., ASSIGNEE TO DE FOREST RADIO TELEPHONE AND TELEGRAPH COMPANY, OF NEW YORK, N. Y., A CORPORATION OF DELAWARE.

APPARATUS FOR AMPLIFYING PULSATING ELECTRIC CURRENTS.

1,348,157.

Specification of Letters Patent. Patented Aug. 3, 1920.

Application filed July 22, 1915. Serial No. 41,332.

To all whom it may concern:

Be it known that I, LEE DE FOREST, a citizen of the United States, residing at New York, county of Bronx, State of New York, have made a certain new and useful Invention in Apparatus for Amplifying Pulsating Electric Currents, of which the following is a specification.

This invention relates to apparatus for amplifying electric currents or oscillations and particularly currents or oscillations of alternating or pulsating character.

The object of the invention is to provide an apparatus of the nature referred to which is simple and efficient for increasing or enhancing the strength of alternating or pulsating oscillatory electric currents.

Other objects of the invention will appear more fully hereinafter.

The invention consists substantially in the construction, combination, location and circuit arrangement all as will be more fully set forth hereinafter, as shown by the accompanying drawing, and finally pointed out by the appended claims.

Referring to the accompanying drawing and to the various views and reference numerals appearing thereon,—

Figure 1 is a view in diagram showing an arrangement of amplifying apparatus embodying the principles of my invention wherein the audions employed are arranged in series or tandem relation.

Fig. 2 is a similar view showing the audions arranged in multiple.

Fig. 3 is a similar view showing still another arrangement embodying the principles of my invention.

I have discovered that the strength of weak pulsating or oscillating electric currents received from any suitable source, such, for instance, as signals received from a distant radio transmitter or otherwise, may be increased, amplified or enhanced by suitably interlinking or associating together a plurality of audions, with their wing or plate and grid electrodes in suitable circuit relation. The audions may be associated together in series or "cascade" arrangement, in multiple relation or otherwise, as may be desired. In case of the multiple relation I prefer to arrange the wing or out-put circuit of the several audions in such manner as to cause all the audions to act simultaneously and accumulatively upon

the signal indicating instrument, such as a telephone receiver or the like.

In Fig. 1 have shown a plurality of audions arranged in series or tandem relation. In this case the source of weak oscillations which are to be amplified, is diagrammatically indicated at 5. As is obvious, this may be any suitable, desired or well known source, and while, therefore, for descriptive purposes I have indicated the secondary coil of a high frequency transformer, it is understood of course that the illustration is purely illustrative and my invention is in no sense to be limited or restricted in this respect.

Reference numerals 6, 7, designate a plurality of bulbs which are shown in the form of standard audions with single plate and grid elements, that is, in the form of evacuated vessels in which are contained the usual plate, grid and filament electrodes, one of such electrodes, in this instance shown as the grid element, being located between the other two. In respect to the number and relative relation or disposition of the electrodes within the evacuated vessels or bulbs, however, my invention, in its broadest scope, as defined in the claims, is not to be limited or restricted.

In the particular arrangement shown, reference numerals 8, 9, 10, designate, respectively the grid, wing or plate and filament elements of audion 6, while reference numerals 11, 12, 13, designate, respectively, the corresponding elements of the audion 7. Current is supplied to the circuits of the filament elements 10, 13, from batteries, or other current sources 14, 15, and the current supply to said circuits may be controlled or regulated in any suitable or convenient manner, as, for instance, by the adjustable rheostats or resistances 16, 17.

In series with the wing or plate elements 9, 12, are batteries or other current sources 18, 19, the positive sides of each of said current sources being connected to its associated wing or plate element, while the negative sides of said current sources are connected to one side of the circuit of the associated filament.

The wing or plate element 9 of the first audion of the series is associated in suitable manner with the grid element of the next audion of the series. This association may be accomplished in various ways. I have

shown a transformer coupling 22, of the auto-transformer type as illustrative of the principles involved.

If desired a "stopping" condenser, 20, 21, 5 may be located in series with the grid elements 8, 11, respectively, of the various audions. The condenser 21 may be omitted if the connection from the transformer 22 to the circuit of the filament 13 of audion 7, 10 is opened.

The signal indicating device is designated by reference numeral 23, and may be in the form of a telephone receiver, as shown, which is arranged in series with the wing or 15 plate element of the last audion of the series.

In the arrangement shown in Fig. 2 the audions 6, 7, are connected up in multiple to the source of vibratory currents, the leads from the current source being connected, respectively, to the grid and filament elements 20 of each audion. In this arrangement, however, the signal receiving device or telephone 23 is associated with the wing or plate circuit which is the out-put circuit, of each 25 audion. This association may be accomplished in various ways. A simple arrangement is shown wherein the circuit of the telephone receiver contains, in series with each other, the secondary coils of transformers 24, 25, the primaries of which are respectively located in the circuits of the wing or 30 plate elements of the audions. It is to be understood, however, that my invention is not to be limited or restricted in respect to 35 the method of associating the signal receiver with the audion circuits. In the particular arrangement shown the various audions act simultaneously and cumulatively upon the receiver, thus securing the combined effect of 40 all the audions.

In the arrangement shown in Fig. 3 audions of the double wing or plate and grid type are employed, the audion bulb 30, having a pair of wing or plate elements 31, connected together, and a pair of grid elements 32, connected together, and a filament element 33, the circuit of the latter including a current source 34, and an adjustable rheostat or resistance 35. Reference numerals 36, 37, 38, 39, and 40, designating corresponding elements of audion 41. In the circuit of the plate elements of each audion is connected a source of current 42, 43, in similar relation and circuit connection to 45 that above described with reference to Figs. 1 and 2. In like manner the circuit of the grid elements of each audion contains a "blocking" condenser 44, 45. The signal receiving device or telephone receiver 46, is 50 shown associated with the various audions of the series in the same manner as above described with reference to Fig. 2. That is to say, the circuit of the receiver is coupled through suitable transformers 47, 48, 55 with the out-put or plate circuits of the

audions, though, as above indicated, my invention in its broadest scope as defined in the claims is not to be limited or restricted in this respect. In the arrangement shown in Fig. 3, however, the grid elements of each 70 audion are connected to the wing elements thereof, instead of the filaments, and such connection is made, in each case, through an inductance 49, 50, across which is connected a condenser 51, 52, respectively. By means 75 of this arrangement each audion becomes an oscillator or source of undamped alternating currents in the interconnected wing and grid circuits. If then, the inductances 49, 50 be suitably associated with a source of received 80 undamped oscillations having a frequency nearly equal to the natural frequency of the oscillating audion circuits, when said oscillating audion circuits are tuned to oscillate in synchronism, beats or 85 interferences are set up in the audion systems and the combined effect of these beat currents is produced and detected in the indicating device 46, which as above explained, is associated with the wing filament circuits 90 of all the audions. Similarly in the circuits 49, 51, and 50, 52, the oscillatory currents induced from the oscillatory circuits of the audions, are combined and cumulative in effect where the inductances 49, 50, 95 are associated, as shown, that is, where each constitutes one coil of a transformer, the other coils 53, 54, of which, are in series with each other and with the source 55 of the received oscillations.

While the oscillating currents generated by such audions and circuits as I have thus far described may be exceedingly minute for purposes of a wave detecting device, I employ the identical arrangements for generation of high power high frequency currents. Inasmuch, moreover, as any receiving antenna re-radiates a portion of the received high frequency energy, the antenna earth system 60, 61, will now radiate the alternating current energy generated in the oscillating audions and associated circuits, so that this antenna-earth system serves equally well as a radio transmitting system. However, my invention, in its broad scope, 115 is not to be limited to antenna-earth or transmitting systems.

While I have shown the plate or wing element of each audion connected to the positive side of an independent battery or 120 current source my invention in its broadest scope as defined in the claims is not to be limited or restricted in this respect.

While I have shown various ways of associating a plurality of audions to secure 125 an amplifying effect upon received weak oscillations my invention in its broadest scope is not to be limited or restricted to the particular arrangements shown and described.

Having now set forth the objects and nature of my invention, and various arrangements embodying the principles thereof, what I claim as new and useful and of my own invention, and desire to secure by Letters Patent, is,—

1: A source of electrical energy, a plurality of oscillating audions, each of said audions having an oscillating circuit connected between two of its electrodes, and means for locally connecting all of said oscillating circuits with said source.

2. A source of electrical energy, a plurality of oscillating audions, each of said audions having an oscillating circuit connected between its two cold electrodes, and means for locally connecting all of said oscillating circuits.

3. A source of electrical energy, a plu-

rality of oscillating audions, each of said audions having an oscillating circuit connected between two of its electrodes, means for electrically associating all of said oscillating circuits with said source, and a receiving circuit common to all of said audions.

4. A source of electrical energy, a plurality of oscillating audions, each of said audions having an oscillating circuit connected between its two cold electrodes, and means for electrically associating all of said oscillating circuits, and a receiving circuit common to all of said audions.

In testimony whereof I have hereunto set my hand on this 15th day of July A. D., 1915.

LEE DA FOREST.
